UNITED STATES PATENT OFFICE.

WILLIAM F. HITCHCOCK, OF HOMER, NEW YORK.

POSITIVE SHUTTLE-MOTION FOR LOOMS.

SPECIFICATION forming part of Letters Patent No. 398,964, dated March 5, 1889.

Application filed December 21, 1887. Serial No. 258,567. (No model.)

To all whom it may concern:

Be it known that I, WILLIAM F. HITCHCOCK, of Homer, in the county of Cortland and State of New York, have invented a new and useful Improvement in Positive Shuttle-Motions for Looms, of which the following is a full, clear, and exact description.

My invention relates to that class of shuttle-motions for looms in which the shuttle is carried back and forth in a positive manner in contradistinction to being thrown, and in which the shuttle is adapted to hold a circular disk-bobbin that carries the filling thread or wire; and is actuated by hollow shuttle-carriers, which are operated intermittently in opposite directions by any suitable positively-acting mechanism, and are provided with catches which operate automatically to engage either carrier alternately with and disengage it from the shuttle or shuttle-frame; and the invention consists in certain details of construction and combinations of parts connected with or comprising the shuttle, its carriers, and engaging and disengaging, catches, substantially as hereinafter described, and pointed out in the claims.

Reference is to be had to the accompanying drawings, forming a part of this specification, in which similar letters of reference indicate corresponding parts in both the figures.

Figure 1 represents a top view of the shuttle and its carriers or carrier-arms with their attached engaging and releasing hooks or catches, one of said carriers being shown in section, and the shuttle being also partly in section and broken away. Fig. 2 is a side view of the same.

A is the circular disk-bobbin, which carries the filling thread or wire, and which is supported by the vertical axial pin b in the shuttle or shuttle-frame B, that carries the bobbin to and fro through the warp, said shuttle being made hollow or of yoke shape in its middle for reception of the bobbin.

C C' are the hollow shuttle-carriers, with which the shuttle is made to alternately engage, and from which it is caused to alternately become disengaged in order to draw the shuttle from side to side of the lathe of the loom when the two shuttle-carriers meet at the middle of the lathe, the engaging and disengaging devices being hooks and catches,

as hereinbefore referred to, but of special construction and arrangement. The general operation, however, is the same as that of other positive shuttle-motions—that is to say, when the loom is set in operation with the shuttle coupled to one of its carriers both shuttle-carriers are simultaneously moved toward the middle of the lathe through the warp wires or threads, and, meeting at the middle, the unoccupied shuttle-carrier disengages the shuttle from the carrier to which it is coupled and becomes itself coupled to the shuttle, and on reversing its motion draws the shuttle through the remaining half of its path through the warp wires or threads. The harness of the loom then shifting the warp wires or threads the shuttle is carried back, the advance part of its motion by the one shuttle-carrier and the latter part of its motion and out at the other side of the warp wires or threads by the other shuttle-carrier. This operation is continuously repeated while the loom remains in operation, the lathe after the laying of each weft-strand moving up in the usual manner and pressing such strand up to the edge of the woven portion of the fabric.

As my invention does not include any special means for operating the lathe or beater, which may be actuated in the usual way and by the mechanism ordinarily employed in both positive motion and other looms, and as the shuttle-carriers may be carried by the beater, so as to move forward and backward with it, and so as to be capable of sliding in direction of their length to positively drive the shuttle as in positive-motion looms generally, and may be actuated to drive the shuttle by the ordinary or any suitable means used in positive-motion looms for the purpose, as, for instance, by the means described in Letters Patent No. 209,439, issued to Horace Woodman, October 29, 1878, no description is necessary or will here be given of such mechanisms or motions.

The shuttle B is provided on its side at the opposite ends of its yoke with notches c c', with or by which the shuttle is secured alternately to its carriers by means of the hooks D D', pivotally connected to the carriers, as at d d', and so that said hooks when working move in horizontal planes, whereby they work horizontally within the warp, which does away

with all possibility of their catching or interfering with the warp. These hooks extend forward of the shuttle-carriers, and are arched to admit of the bobbin freely within them, 5 and their outer ends, *e*, are made inclined or wedge-shaped, so that each when coming in contact with the other will be alternately raised or released by it and the other hook engaged with its respective shuttle-notch *c* or *c'*. If desired, the outer ends, *e e*, of said hooks may, as shown, be made broad, so as to cover the entire width or edges of the bobbin, and thereby insure proper action when coming together. Practically—that is, so far as 10 any possible interference of the shuttle with the warp in its passage therethrough is concerned—only the curved ends of these catches or hooks *D D'* protrude from the carriers *C C'*, and said hooks being smooth and free from 15 corners cannot possibly catch the warp, and a broken thread will slide over them and in no wise prevent their proper action. By the arrangement of these hooks, as shown, they have no tendency to throw the shuttle out of its line even when a little worn, and by reason of 20 their shape, arrangement beyond or outside of the peripheral portion of the bobbin, and horizontal motion, a much larger bobbin than is ordinarily admissible may be used, the action 25 of the catches not interfering with the rotation of the bobbin.

The hooks *D D'* are self-closing by means of independent springs, which are necessary when weaving wire. Thus springs *f* are here 30 shown, preferably, of an elongated construction and arranged within the rear or pivot ends of the hooks *D D'*, made bifurcated for the purpose, said springs being applied to the backs of the hooks *D D'*, to alternately close 35 them into engagement with their respective notches *c c'* in the shuttle, as or after the other one of said hooks has been disengaged by the meeting of the outer inclined ends, *e*, of the hooks, to transfer the shuttle from one carrier, *C* or *C'*, to the other for continuance of 40 the motion of the shuttle through the warp.

Each carrier *C C'* is of tubular construction and may be fitted internally back of its front end portion with a spring-cushion, *E*, which, 45 as shown, consists of a simple spring and plunger forced outward by the spring. These spring-cushions serve to ease the blow, shock, or jar consequent upon the entry of the shuttle within the two carriers alternately, or as 50 the carriers receive and deliver or transfer the shuttle from one carrier to the other, the opposite ends or noses of the shuttle bearing against the yielding cushions. Said cushions

also serve to make either hook *D D'* securely hold its own in the notch *c* or *c'* of the shuttle 60 while it is in engagement with when the released carrier is away from the shuttle, the springs *f* applied to the hooks operating to keep the latter always in their proper position for latching. 65

The automatic catching and releasing of the shuttle with and from the two carriers, as described, and whereby independent inclines to control the action of the hooks are dispensed with, form an important feature of my 70 invention. These inclines may, however, if required, be used and are formed by gaining grooves *s s* into the side of the shuttle from opposite ends thereof and terminating at their inner ends in inclines *s' s'*. The grooves *s s* 75 are parallel with the longitudinal axis of the shuttle, which allows the hooks to slide parallel along them and then up the inclines *s' s'* at the proper moment, and so aid and steady the hooks as they lift one upon the other. 80

Having thus fully described my invention, I claim as new and desire to secure by Letters Patent—

1. The combination, with a shuttle, *B*, consisting of a yoke having vertically-aligned 85 bobbin-bearings, diametrically-opposite projecting ends, and notches *c c'* on one side of the shuttle and where the said projecting ends join the yoke, of the tubular shuttle-carriers having arch-shaped hooks *D D'* pivoted at their outer ends to the same side of the carriers, with their axes parallel with the said bobbin-bearings and constructed to travel along the projecting shuttle ends and engage the notches therein, and the springs 90 throwing the hooks toward the open side of the yoke, substantially as set forth.

2. The combination of the shuttle *B*, having a central yoke, side notches, *c c'*, at opposite ends of the yoke, and opposite end side 100 grooves, *s s*, terminating in inclined inner ends, *s' s'*, the tubular shuttle-carriers *C C'*, and the horizontally-operating arch-shaped hooks *D D'*, pivoted to said carriers and constructed to travel within the grooves *s s* up 105 the inclines *s' s'* and to engage with the notches in the shuttle, also having inclined outer ends adapted to lift or release the one hook by the other, and springs operating to latch or close the hooks into engagement with 110 the shuttle, essentially as set forth.

WM. F. HITCHCOCK.
